Inventor:
John H. Ames,
by *John W. J. Howard*

UNITED STATES PATENT OFFICE.

JOHN H. AMES, OF ST. PAUL, MINNESOTA.

RAILWAY-SIGNAL.

SPECIFICATION forming part of Letters Patent No. 328,913, dated October 27, 1885.

Application filed July 14, 1884. Serial No. 137,687. (No model.)

To all whom it may concern:

Be it known that I, JOHN H. AMES, of St. Paul, in the county of Ramsey and State of Minnesota, have invented certain new and useful Improvements in Railway-Signals, of which the following is a specification.

This invention has reference to that class of signals which are employed to indicate the condition of the track or tracks of a railroad at yards, switches, junctions, crossings, drawbridges, tunnels, curves, or other portions of the track, or for block and other signaling, and may be used in connection with any mechanical, electric, or other system of interlocking, whereby to guard the tracks, switches, crossings, &c.

The invention has special reference to means for restoring or moving the signal, whether for day or night use, automatically to a normal position. This normal position may be that in which the signals are placed to indicate "safety," "danger," "caution," "orders," or any other information previously agreed upon and understood by the railroad officials or operatives.

The invention is intended, more particularly, for use in connection with a target and lantern, the former for day and the latter for night use, the object being to automatically restore the target and lantern to the normal position from which they have been moved by the operator, whether standing in the neighborhood of the signal or in a cabin or signal-station remote from the signal.

In the accompanying drawings, Figure 1 is a side elevation of a structure embodying my invention and showing its application in a simple form. Fig. 2 is a top view or plan of Fig. 1. Fig. 3 shows a side elevation of a modified form of the invention. The preceding figures are intended for use with a single-track road. Fig. 4 shows a form of the invention as applied to a double track. Fig. 5 shows a modification also for a double track. Fig. 6 shows a modification applied to either a single or double track.

Similar letters of reference indicate similar parts in the respective figures.

In all forms of the invention it is intended to operate the day signal or target in connection with a night signal or lamp, or its equivalent, the day and night signals being restored

to the normal position from which they have been previously turned by the elastic force of a spring or weight, or spring and weight combined, the tendency of which is to restore the signals to their said normal position. The spring alone is, however, preferred, and the description of my invention hereinafter given will refer chiefly to the spring.

A is the day signal or target, and B is a lamp having lenses of different-colored glass, as ordinarily constructed. Each lamp will preferably contain four lenses, the opposing lenses being of the same color—thus, for instance, two lenses opposing each other may be of red glass, and the lenses at a right angle thereto of green glass—all as well known heretofore.

The target and lantern are mounted upon a common revolving shaft, C, preferably standing in a vertical line and turning in bearings a. The target and lantern thus arranged may be placed upon a tower or post, D, of sufficient altitude to enable the signal to be readily seen by an approaching train, or otherwise conveniently located, as heretofore well known. The shaft C is provided with a crank-arm, b, having a pin, b', to which a rod, d, is attached. The rod d is adapted to move longitudinally and loosely in a bracket or bearing, e, secured to the tower, post, or other support. Mounted upon the said rod d, and extending between the bracket e and a collar, f, secured to the rod, is a spiral spring, g. The outer end of the rod d is provided with a ring, h, or other device, by means of which a rope, i, may be attached to it, which rope leads to the point or locality at which the operator stands to actuate the signal.

It will be understood that the arms of the target are preferably four in number, which are of contrasted colors to correspond with the indications of the lantern.

The figures show all of the signals in their normal position, or that previously agreed upon as normal, whether indicating "danger," "safety," or other condition.

When it is desired to change the signal from the normal position to a state indicating an opposite condition, the operator draws upon the rope i, causing a quarter-revolution of the shaft C and the consequent quarter-revolution of the target and lamp, bringing the necessary

color of the target and lamp to stand in view of an approaching train. The cord *i* may be operated by hand, or may form a part of a general system of signaling, and be used in connection with interlocking mechanism, all as heretofore well known.

Upon the release of the means which hold the cord drawn back, whether such means are hand or mechanical, the expansive force of the spring gives a quarter-turn backward to the crank-arm *b*, and consequently causes a corresponding quarter-rotation of the shaft which carries the target and lantern, the signals being thus restored to their normal position.

15 The above description refers more particularly to Figs. 1 and 2.

Fig. 6 shows the invention applied to a sliding target.

20 In Fig. 3 a spring similar to that described with reference to Figs. 1 and 2 is used, but instead of mounting the lamp upon the shaft bearing the target, a supplemental crank, *k*, is placed upon said shaft, which, by a rod, *k'*, attaches to a slide, *l*, which works in connection with a stationary lamp. It will be understood that the slide is provided with a glass of a color different from that of the glass or lens properly belonging to the lamp, which 25 glass or lens is of a color used to indicate the normal condition. Therefore the normal condition of the lamp is that in which it is shown in the figure, namely, with the slide withdrawn from its face, the color of the target 30 which is exposed to view when the slide is withdrawn corresponding with the color of the glass or lens proper to the lamp.

35 In Fig. 4, in which the invention is shown applicable to a double-track road, a target and

lamp are suspended over each track to constitute a complete signal, operating in the manner explained with reference to Figs. 1 and 2, each being independent of the other. In addition, a stationary lamp or lantern is situated between the two tracks, having slides of 40 the proper colors connected by rods *m*, with supplemental cranks *n* mounted upon the rotary shafts, as explained with reference to Fig. 3. This figure shows a combination of the systems illustrated in Figs. 1, 2, and 3. 45

50 As a further modification, the lamp may be movable and the colored slide stationary, as shown in Fig. 5.

Having described my invention, I claim—

1. In a railroad signaling device, a signal-shaft capable of partial rotation and carrying signals, a crank-arm upon said signal-shaft, a rod connected to said crank-arm capable of longitudinal movement, and having thereon a spring adapted to be compressed by 60 force exerted longitudinally upon said rod, and by its expansive force to reset the signal-shaft to its normal position, all combined substantially as set forth.

2. In a railroad signaling device, the combination of a signal-carrying shaft capable of a partial rotation, a crank-arm, a stationary lamp, a movable slide operating in connection with the stationary lamp, and a spring for restoring the signals to their normal position, 65 all combined substantially as set forth.

70 In testimony whereof I have hereunto set my hand.

JOHN H. AMES.
